FLUID FUEL BURNER

Reginald W. Beckett, Elyria, Ohio

Application March 14, 1950, Serial No. 149,550

4 Claims. (Cl. 158—76)

This invention relates to fluid fuel burning heating devices and has particular reference to oil burners of the pressure atomizing type in which fuel oil is discharged under pressure through a small orifice or nozzle into a combustion chamber and is burned while suspended in the combustion air that is supplied by a power driven fan. The present application is a continuation in part of my copending applications for patent Serial No. 766,967 filed August 7, 1947 for Fan Regulator, now United States Patent 2,506,192 and Serial No. 24,559 filed May 1, 1948 for Oil Burner of the Atomizing Type, now United States Patent 2,599,153. Reference is made to copending application for patent Serial No. 152,353, filed 28 March 1950, for Fluid Fuel Burner for Free Standing and Plate Mounting Installations, now United States Patent 2,777,509.

Oil burners of the type involved in the present invention have been highly developed and are presently in common use in large numbers. There are, however, a number of desirable improvements that are continuously being sought. Primarily it is desirable to reduce the cost of manufacture of these burners so as to make them more readily available to the public at large. Other improvements needed are along the lines of greater efficiency, quieter operation, and safety.

It is therefore the principal object of the present invention to provide a generally improved oil burner construction of the pressure atomizing type which achieves the improvements referred to and in which numerous advantageous features of construction and arrangements of parts have been incorporated to obtain economic manufacture and operation, relatively silent operation, and safety.

Economy is obtained by unique design features which facilitate assembly with a minimum of machining of parts and without special skill or the necessity for the use of special tools, jigs, and fixtures. Reduced cost is also obtained by the elimination of parts to simplify the design of the burner and the assembly and installation thereof.

A still further object is to provide an improved arrangement for mounting a control box and connecting electrical controls for pressure atomizing burners of the type that employ electrical ignition in combination with electrical controls.

Still further objects and advantages relate to structural details and novel combinations and arrangements of parts which will become apparent as the description proceeds. This description is made in connection with the accompanying drawings forming a part of the specification. Like parts throughout the several views are indicated by the same letters and numerals of reference.

In the drawings:

Figure 1 is a side elevational view partly in section and with parts broken away and removed showing one form of fluid fuel burner structure embodying certain features of the invention;

Fig. 2 is an isometric view of a box containing a combustion control apparatus showing the terminal screws

which register with and contact the electrical terminals of the junction box on one side of the burner structure of Fig. 1;

Fig. 3 is a schematic wiring diagram showing electrical connections associated with the control for the burners; and

Fig. 4 is a fragmentary front end view looking into the air tube of the burner, this view being taken substantially along the line indicated at 4—4 of Fig. 1.

10 The burner of the present invention as illustrated in Figs. 1 through 4 comprises an air pumping structure that includes an upright housing structure of generally ovate form having spaced substantially parallel front and rear walls 1 and 2 respectively, substantially parallel side walls, the near side being indicated at 4 and a curved top wall 5. The housing is of cast metal such as iron or aluminum and includes a bottom 6 which is integral with the front and rear walls.

20 The housing is supported on a pedestal structure which comprises a cast metal base 7 and one or more supporting or spacing blocks or shells 8 and 9. One feature of the present oil burner construction that is of particular advantage relates to the spacing or supporting shells, the number of which can be increased or decreased to vary 25 the height of the housing above the base 7. These shells or blocks, of cast iron or aluminum, are of square or other non-circular plan form.

25 In each corner of the spacing shell is an integral column which projects below the level of bottom edges 11 of 30 the shell so as to provide depending foot portions 12 received in interlocking relation in mating recesses formed in the top of the base 7 or in the top of the next lower spacing shell. The base 7 has a square depressed area in its top and is formed with integral thick sectioned 35 bosses 17 in the corners of such area, the bosses having flat tops below the level of the top edge of the base.

35 The upper shell 8 differs slightly from the intermediate or spacing shell 9 in that the columns thereof extend upwardly above the level of the top edge of the side walls 40 providing lugs 18 which interfit in mating relation in the corners of a square socket in the bottom 6 of the housing. The interfitting feet and sockets on the ends of the columns prevent relative turning of the spacing shells on one another, on the base 7, and in the housing bottom 6 so that the housing structure is maintained in pre-determined non-rotative position relative to the base. Although only two shells are shown it is contemplated to use an additional number of the intermediate shells 9 if greater height is desired, or to lower the housing, the spacing shell 9 may be eliminated or the burner mounted directly on the base 7.

45 The housing is secured to the base by a vertical stud or through bolt 19 the upper end of which is threadedly secured in the housing bottom 6 and the lower end of 50 which extends downwardly through an opening centered in platform portion 20 of the base. A nut 21 is tightened against the underside of the base platform to hold the assembly together.

55 An electric motor 22 supplies the energy for driving a squirrel cage fan or sirocco type blower 23 which is received in a chamber formed in the upper portion of the housing. The fan, inserted into the blower chamber through a large diameter opening 31 provided in the rear wall 2 of the housing, is secured on one end of the motor shaft 25. The motor shaft portion which projects from the other end of the motor is surrounded by a bell-shaped support member 28 secured to the motor by diametrically located cap screws, one of which is indicated at 29. The small end of the bell member 28 is formed with a sleeve 32 to receive a plug portion of a fuel oil pump 35.

60 The pump is disposed in end to end coaxial relation to the motor shaft and a flexible drive coupling connects

the shaft ends. One or more set screws 40 threaded through the bell sleeve 32 are engaged in detents in the pump plug to lock the latter in the bell member sleeve and to retain the pump in predetermined upright position.

A bracket 42 having a transversely curved body portion 43 is concave on its underside so as to fit over and partially embrace the top of the motor. At one end of the curved body 43 the bracket is formed with an integral depending flange 44 which is disposed flatwise against the rear wall 2 of the housing structure and is secured to the latter over the opening 31 by cap screws 45. The bracket flange 44 has a relatively small opening 46 which closely surrounds the motor shaft end 25.

Along opposite sides of the bracket at the lower edges of the arcuate or curved body 43 are horizontal portions or lateral extensions 47 which terminate in depending flanges 48. Rubber tension type suspension members 50 are secured by bolts 51 to the underside of the lateral bracket extensions.

One pair of the resilient rubber members 50 are attached by bolts to half straps 54 which cooperatively embrace the motor 22, the bolts passing through radial ears on the ends of the half straps and being threaded into metal elements embedded in the rubber of the suspension members. One of the half straps passes over the top of the forward portion of the motor and is disposed underneath the curved body portion 43 of the bracket. The other half strap 54 extends underneath the forward portion of the motor to support the latter. The other pair of the resilient rubber suspension members 50, which depend from portions of the bracket extensions 47 that project rearwardly of the curved body portion 43 of the bracket, are secured by bolts 56, threaded into embedded metal elements, to diametrically disposed integral ears 57 which extend outwardly from opposite sides of the bell-shaped support member 28.

Air is drawn into the fan chamber through an opening in the front wall 1 of the housing. Disposed against the outside of the front wall 1 of the housing and over the air inlet opening into the fan chamber so as to control the flow of air through such opening, is a hood 60 which may be of cast metal.

The hood is open across the bottom to permit the inflow of air under the control of a sheet metal gate pivotally mounted off center for turning movement about a horizontal axis. The gate is supported on pins 66 that are threaded through aligned openings in bottom portions of the side walls, the pins being held against turning by lock nuts 67.

The rear edges of the hood are directed toward an integral outstanding rib 69 which is formed on the front wall 1 of the housing and has the same contour or outline shape as the edges of the hood walls. The hood does not make peripheral contact with the housing rib 69 but is spaced therefrom by three integral bosses or raised portions, one of which is indicated at 70. Cap screws or bolts 72 pass through openings in ears 73 provided one on each side of the hood and are threaded into the front wall 1 of the housing structure. Each of the cap screws 72 is located between a top spacing boss and a side spacing boss so that the hood is held by three-point contact tightly against the housing structure, there being a clearance 74 between the edges of the hood walls and the rib 69.

In adjusting the burner for different oil rates the quantity of combustion air drawn into the fan chamber through the opening in the bottom of the hood 60 is regulated by controlling the extent to which the gate opens. Customarily the amount of opening of the air inlet control gate is adjusted while the burner is in operation by means of a rod which extends vertically through the interior of the hood. A knurled thumb wheel 80 is threaded onto the top of the gate adjusting rod above the top wall of the hood and is held against turning on the rod by lock nut 81.

Below the air induction hood 60 an elongated tapered tube 86 of circular cross section is attached by bolts 87 to the front wall 1 of the housing structure over an opening which communicates with an air passage formed in the housing structure below the fan chamber. Combustion supporting air drawn into the housing through the hood 60 is forced by the fan 23 down into the air chamber in the bottom of the housing and thence out through the circular passage in the air tube 86 and through a burner head 90 which extends through the walls of the fire box of the combustion chamber, not shown.

Fuel oil from a source not shown is supplied by the pump 35 and forced from the latter through a bendable conduit 88 which may be of copper to a rigid conduit 89 supported by a bracket 91 so as to extend longitudinally through the center of the air tube 86. Forwardly of the bracket 91 the fuel conduit 89 carries a spider 93 that locates the conduit in the center of the air tube. A hollow manifold 94 is threaded on the end of the conduit 89 and mounts a pair of nozzles 95. The sparking ends of ignition electrodes 96 are received through spaced insulators, one of which is indicated at 97, supported by clamps 98 mounted on the rigid fuel conduit 89.

Electrical current for energizing the ignition spark across the ends of the electrodes 96 is supplied by a transformer 100 hinged along one edge to the housing for turning movement about a vertical axis. The transformer is normally disposed across an opening through the rear wall 2 of the housing structure and has a pair of electrical terminals which extend into the air chamber in the bottom of the housing. The transformer serves as a closure for the opening in the rear wall and the electrodes 96 carry contact elements that automatically make electrical connection between the electrodes and the transformer terminals when the transformer is swung to closed position across the housing opening.

The rigid fuel conduit 89 and the electrodes 96 and the other parts carried thereby comprise an assembly which is removable as a unit from the air tube for replacement or adjustment. The bendable conduit 88 extends through a lateral extension of the rear opening in the housing structure to one side of the transformer 100 and is disconnected from the fuel pump 35 when it is desired to remove the fuel conduit and ignition electrode assembly from the burner. A base portion 101 on the bracket 91 is contoured to correspond to the curvature of the bottom of the air chamber of the housing and is apertured to receive an upstanding bolt 102 that extends upwardly through a hole in the bottom 6 of the burner housing. A nut 103 on the bolt 102 is tightened down against the base 101 of the bracket to secure the latter in place, the bolt having a square or non-circular head 104 that is received in a mating recess formed in the underside of the housing bottom 6 so as to prevent turning of the bolt when tightening or loosening the nut 103.

An integral finger 105 which extends inwardly from one of the walls of the uppermost spacing block 8 engages the head 104 of the bolt to prevent the bolt from dropping out of the hole provided therefor in the housing bottom 6. Thus the bolt is retained in place when the nut 103 is removed for withdrawal of the ignition electrode and fuel conduit assembly. This particular arrangement for retaining the bracket locking bolt 102 reduces the assembly cost of the burner, since machining of the casting which constitutes the burner housing is avoided. Furthermore, the bolt 102 can be readily replaced should it be broken or damaged.

Control of the electrical current to energize the motor and the transformer is effected by means such as the electronic combustion safety system manufactured by Minneapolis-Honeywell Regulator Company and known as the R177A relay and the Series 10 controller. The side wall 4 of the burner housing is formed to receive a junction box 106 to which is mounted the control mecha-

nism. Electrical leads or wires 111 and 112 from the motor 22 are contained in an insulated conduit 107 which runs through an opening in the rear wall of the housing and through an internal chamber of the housing, the leads being brought into the junction box and connected to terminals 108 and 109. Leads or wires 114 and 115 from the transformer 100 are also contained in an insulated conductor or conductors which extend through an internal chamber in the burner housing and are brought into the junction box and connected one to the terminal 108 and the other to terminal 110.

A wiring diagram showing suitable electrical connections for the burner is illustrated in Fig. 3, the showing being purely diagrammatic and relating to the above mentioned electronic safety system. Power or electrical current is supplied to the system through line conductors L-1 and L-2 which are brought into the junction box 106 and connected respectively to terminal 119 and the terminal 108 therein. The relay of the safety combustion control mechanism for governing the burner operation is contained in a metal box 113 which fits over the junction box 106. Electrical connection is made with the various terminals in the latter by captive screws 124 or other means. Besides the motor and transformer, other devices such as the above mentioned Series 10 controller indicated at 116, and a limit control indicated at 117 may be connected into the control mechanism through the junction box 106, the leads or wires from these devices being attached to terminals in the junction box that are contacted by the captive screws 124 of the relay box.

The control system mentioned above employs a conventional photoelectric or phototube cell 118 to monitor the operation of the burner. In starting up the burner, the photocell responds to the establishment of a flame by effecting de-energization of the electric ignition while maintaining the motor in operation to feed oil and air. Upon flame failure, the photocell functions to effect energization of the electric ignition and to place the electric heater of a thermal safety switch in the motor circuit. The safety switch shuts down the system if ignition is not reestablished within a pre-determined time interval. Establishment of a lasting flame, however, stimulates the photocell to effect ignition cut-off and to shut out the heater of the safety switch so that burner operation continues.

The photoelectric cell or phototube can be located in any suitable position where it is exposed to the light rays emanating from the burner flame. As a particularly advantageous location the present invention provides means for mounting the photocell 118 in the air tube 36, in a container 125 which faces toward the open mouth of the burner head 90. The container is supported on a bracket 120 which is slideable to different positions along the rigid fuel conduit 89.

A flexible electric conductor 121 is connected to the anode of the photocell 118 through the rear of the casting 125 and extends through the air tube and the air chamber in the bottom of the housing, thence through the aforesaid internal chamber of the housing and into the junction box 106 where it is connected to terminal 122. The phototube cathode is grounded to the burner housing structure through the adjustable bracket 120 and the ignition electrode and fuel conduit assembly. Thus the photocell conductor is contained wholly within the housing structure of the oil burner so as to be protected against displacement and damage. Furthermore, the photocell, located in the air tube adjacent the rear end thereof is customarily cooled by the air flowing thereover while the burner is in operation.

Although the photocell mount is shown closely adjacent the supporting bracket 91 the bracket 120 may be moved forwardly on the conduit 89 to a position in which the photocell is closer to the burner head. The particular location of the photocell along the length of the fuel conduit 89 supporting the same may be varied to suit

the particular conditions and requirements of any one burner installation. For example, the air tube 36 may be considerably longer than shown and in lengthy air tubes it may be desirable to move the photocell forwardly, relatively closer to the burner head and away from the ignition electrode bracket 91. A set screw 123 is provided in the photocell bracket 120 to retain the latter in adjusted position on the rigid oil conduit so that the bracket does not become displaced upon removal of the assembly in service.

In accordance with the patent statutes the principles of the present invention may be utilized in various ways, substitution of parts and changes in construction being resorted to as desired, it being understood that the embodiments shown in the drawings and described above are given merely for purposes of explanation and illustration without intending to limit the scope of the claims to the specific details disclosed.

What I claim and desire to secure by Letters Patent of the United States is:

1. In a pressure atomizing fluid fuel burner of the type having a structure for pumping air into a combustion chamber, said structure including a hollow housing and an air tube extending from the housing for conducting combustion air to be discharged through one end of the air tube, said burner having ignition electrodes and a fuel supply tube connected together as an assembly and extending through an air tube, a combustion control system contained in a box having captive electrical terminals arranged in a predetermined pattern, a junction box mounted externally on and wholly supported by the air pumping structure, said junction box having an open side and a plurality of fixed electrical terminals exposed on said open side and arranged in a predetermined pattern complementary to the pattern of the control box terminals for mounting of the control box on and over the open side of the junction box and for facile connection of the control box terminals to the junction box terminals in predetermined relation, a light responsive control element, means supporting such control element within the pumping structure in position to receive directly radiant energy admitted into the air tube through said one end, and electrical conductor means extending between the control element and the junction box terminals, said conductor means being located substantially wholly within and protectively enclosed by the pumping structure.

2. In a pressure atomizing fluid fuel burner of the type having a structure for pumping air into a combustion chamber, said structure including a hollow housing and an air tube extending from the housing for conducting combustion air to be discharged through one end of the air tube, a fan in the housing, an electric motor mounted on the air pumping structure and operatively connected to the fan to actuate the latter, said burner having ignition electrodes and a fuel supply tube connected together as an assembly and extending through the air tube, a combustion control system contained in a box having captive electrical terminals arranged in a predetermined pattern, a junction box mounted externally on and wholly supported by the air pumping structure, said junction box having an open side and a plurality of fixed electrical terminals exposed on said open side and arranged in a predetermined pattern complementary to the pattern of the control box terminals for mounting of the control box on and over the open side of the junction box and for facile connection of the control box terminals to the junction box terminals in predetermined relation, a light responsive control element, means supporting such control element within the pumping structure in position to receive directly radiant energy admitted into the air tube through said one end, electrical conductor means extending between the junction box terminals and the electric motor, electrical conductor means extending between the junction box terminals and the control element, said control element conductor means

7
and said motor conductor means both passing into the junction box through another side of the latter, and said control element conductor means being located substantially wholly within and protectively enclosed by the pumping structure.

3. In a pressure atomizing fluid fuel burner of the type having a blower structure for pumping air, said structure including a hollow housing, an air tube extending from the housing and having walls defining an internal passage continuous with the interior of the housing for receiving air from the latter and conducting the received air to one end of the air tube for discharge into a combustion chamber, said burner having ignition electrodes and a fuel tube connected together as an assembly and extending longitudinally through the air tube passage, said blower structure including a fan and electric drive means for the fan carried by the housing, said burner including electric transformer means carried by the housing for supplying ignition current to the electrodes of the assembly, a combustion control system comprising a box having captive electrical terminals arranged in a predetermined pattern, a junction box mounted externally on and wholly supported by the housing of the blower structure, said junction box having an outwardly facing open side and a plurality of fixed electrical terminals exposed on said open side and arranged in a predetermined pattern complementary to the pattern of the control box terminals for mounting of the control box on and over the open side of the junction box for facile connection of the control box terminals to the junction box terminals in predetermined relation, and electrical conductor means extending between the junction box terminals and both the electric fan drive means and the electric transformer means, said electrical conductor means from both the drive means and the transformer means passing into the junction box through the interior of the housing and through another side of the junction box.

4. In a pressure atomizing fluid fuel burner of the type having a structure for pumping air into a combustion chamber, said structure including a hollow housing and an air tube extending from the housing for conducting combustion air to be discharged through one end of

5 the air tube, a fan in the housing, an electric motor mounted on the air pumping structure and operatively connected to the fan to actuate the latter, ignition electrodes and a fuel supply tube connected together as an assembly and extending through the air tube, an electric transformer mounted on the structure, means electrically connecting the transformer to the ignition electrodes of the assembly, a combustion control system contained in a box having captive electrical terminals arranged in a predetermined pattern, a junction box mounted externally on and wholly supported by the air pumping structure, said junction box having an open side and a plurality of fixed electrical terminals exposed on said open side and arranged in a predetermined pattern complementary to 10 the pattern of the control box terminals for mounting of the control box on and over the open side of the junction box and for facile connection of the control box terminals to the junction box terminals in predetermined relation, a light responsive control element, means supporting such control element within the pumping structure in position to receive directly radiant energy admitted into the air tube through said one end, electric conductor means extending between the junction box terminals and both the motor and the transformer, electrical conductor means extending between the junction box terminals and the control element, said control element conductor means and said motor and transformer conductor means all passing into the junction box through another side of the latter, and said control element conductor means being located substantially wholly within and protectively enclosed by the pumping structure.
